UNITED STATES PATENT OFFICE.

ARTHUR C. SCHLOTH AND HERMAN E. SCHLOTH, OF LYNN, MASSACHUSETTS,
ASSIGNORS TO ULDORIC J. BOUCHARD, OF BOSTON, MASSACHUSETTS.

ALARM.

1,406,762.

Specification of Letters Patent. Patented Feb. 14, 1922.

Application filed November 8, 1920. Serial No. 422,642.

To all whom it may concern:

Be it known that we, ARTHUR C. SCHLOTH, and HERMAN E. SCHLOTH, citizens of the United States, residing at Lynn, in the county of Essex and State of Massachusetts, have invented new and useful Improvements in Alarms, of which the following is a specification.

Our present invention has reference to alarms.

Our object is the construction of means for continuously sounding an alarm when an attempt has been made to open a door by an unauthorized person not acquainted with the means for releasing the door locking means.

The improvement is susceptible for use in connection with safes, automobiles, or in fact any mechanism or machinery wherein the contents thereof are to be guarded or the operation of the machinery prevented by other than authorized persons. The same includes an electrically operated alarm having a switch controlled normally open circuit which is concealed in a casing that is closed by a door, the said door having means, including a permutation lock for holding the same closed, the lock also carrying a cam member which is in the path of engagement with a spring influenced push member or button for the switch so that when brought in contact therewith the circuit will be completed and the alarm sounded, means automatically holding the circuit closer in closing position, whereby the alarm will be continuously sounded until the person acquainted with the combination and means for opening the door, operates the same, the continuously sounding alarm directing attention to the fact that a surreptitious attempt has been made at opening the door.

The foregoing, and many other objects which will appear as the nature of the invention is better understood, may be accomplished by a simple construction, combination and operative arrangement of parts, such as is disclosed by the drawings.

For the sake of convenience, we have illustrated our alarm in connection with an automobile, whereby the horn thereof will be sounded when an unauthorized attempt has been made to operate the same, but, of course, the improvement is not to be thus

restricted in its useful application. Also 55 the drawings illustrate a satisfactory embodiment of the improvement and are susceptible to such changes and modifications as fall within the scope of what we claim.

In the drawings:—

Figure 1 is a view of our improvement applied on the dash of an automobile.

Figure 2 is a similar view with the door for the casing in which the starting switch for the automobile is arranged and also in 65 which the circuit making and breaking means for the alarm is arranged.

Figure 3 is a sectional view approximately on the line 3—3 of Figure 2, on an enlarged scale, and illustrating the arrangement of 70 parts when the door is locked.

Figure 4 is a substantially similar view but showing the arrangement of parts when an attempt has been made by an unauthorized person to open the door of the switch 75 box.

Figure 5 is a sectional view on the line 5—5 looking in the direction of the door, the parts being arranged as illustrated in 80 Figure 3.

Figure 6 is a similar view with the parts arranged as illustrated in Figure 4.

Figure 7 is a longitudinal sectional view approximately on the line 7—7 of Figure 6, on an enlarged scale.

Figure 8 is a view of the circuit breaker.

On the dash 1 of an automobile 2 we arrange our improvement. The improvement includes a substantially rectangular casing 3 that is let into the dash so that its outer 90 face is flush therewith. The outer face of the casing is open and the said opening is normally closed by a hinged door 4. The door on its outer face has a keeper 5 to be engaged by a pivoted latch 6 supported on the 95 door casing. On the inner face of the door there is secured a depending angle bracket 7, while in the bottom of the casing there is journaled on suitable supports 8 a turnable member 9 which is really in the nature 100 of a rod that has a portion thereof threaded, as at 10. The outer end of the rod 9 is received in a round opening 11 in one of the sides of the casing, and the said end of the rod is squared or otherwise shaped to receive the socket of a key (not shown). As the face of the casing is arranged flush with the dash of the automobile the squared

end of the rod is normally concealed so that only persons acquainted with the construction can apply the key. On the threaded portion of the rod 9 is an angle member 5 that constitutes a latch 12. One arm of the said member has a threaded opening therethrough which is engaged by the threads of the bolt 9, and it will be apparent that by turning the bolt the latch may be brought 10 to engage with the bracket or keeper 7 on the door, and thus hold the door closed on the casing.

On the inner face of the door there are the disk tumblers of a permutation lock. 15 In the showing of the drawings, I have illustrated only three tumblers, 13, 14 and 15 respectively. The tumbler 15 is in the nature of a cam member, and all of the tumblers have peripheral notches which are 20 designed to align when the lock is properly operated. The tumbler 14 has an arcuate opening 16 therein concentric with the longitudinal axis of the pivot member 17 for all of the tumblers. The tumbler 13 has a pin 25 18 that is received in the opening 16. The tumbler 13 also has its periphery provided with one or more substantially V-shaped notches 19. On the inner face of the door, and contacting with the periphery of the 30 tumbler 13 is a yieldable brake member 20 that holds the said tumblers against accidental turning.

The tumbler 13 has a hub 23 that passes through an opening in the door, and on the 35 outer face of the said hub is a flanged disk in the nature of a dial 24. The pivot 17 passes through the hub and dial and has on its outer end an operating knob 26. Thus the outer tumblers 14 and 15 are operated 40 independently of the inner tumbler 13, which latter is turned by the turning of the dial, the latter having its outer face provided with an annular enlargement for this purpose.

45 Pivots secured to the inner face of the door, over the inner tumbler 13 are dogs 27 respectively. These dogs have their active faces substantially V-shaped in plan and are oppositely directed. The pivots for the dogs 50 pass through suitable openings in the door and have on their outer end knobs 28 respectively. The pivots for the dogs pass freely through the openings therefor in the door 4, so that the dogs will freely drop on 55 to the periphery of the tumbler 13. It will be apparent that should either of the dogs have their active face drop into either the keeper notch 16 of the tumbler 13 or the V-shaped or retarding notch 19 of the said 60 tumbler, the latter cannot be turned unless the dogs are swung upwardly into contact with the inner face of the front of the casing 3. When in such position, the dogs frictionally contact with the said inner wall of 65 the casing so that they are held out of con-

tacting engagement with the tumbler. These dogs add to the confusion of unauthorized persons in their attempt to open the door 4.

Projecting into the door is a keeper 29. When the proper tension has been reached 70 so that the slots or notches 16 of the respective tumblers 13, 14 and 15 have been brought opposite the keeper, and the dogs have been brought out of contacting engagement with the upper wall of the casing, and 75 also when the slid able latching means has been moved to unlatching position, the door can be opened.

In the casing is the switch of the electric circuit of the automobile, and also in the 80 casing is the alarm switch. This switch is preferably connected to the local circuit including a battery 33 and an alarm 34. In arranging the device on an automobile, the alarm is preferably in the nature of the 85 horn for the machine. One of the elements 35 of the switch 32 is of spring construction and is normally out of engagement with its contact 36.

The circuit closer, for the alarm circuit, 90 includes an element 37 of insulating material and which is connected to a spring arm 38 that is supported at its rear end on a bracket 39 that is secured to the side wall of the casing. The arm is also received in a 95 guide bracket 40 and is limited in its outward movement by contact with a finger 41 formed on a plate 42 that has an angle end which is secured to the side of the casing. Pivotally secured, as at 43 on the arm 38 is 100 the inner angle end 44 of a latch member 45. The latch member has its outer end formed with a downturned portion which is bifurcated at its lower end to provide an outer arm 47 and an inner arm 48, the 105 inner arm being longer than the outer arm and normally contacting with the inner face of the arm 38. The outer arm 47 normally rests on the upper straight edge of the finger 41, but will be moved off of the 110 said finger and by the weighted free end of the latch 45 to drop on the arm 38 against the inner wall of the finger when the circuit closer has been moved to close the alarm circuit and sound the alarm. The alarm will 115 be sounded as long as the latch member is in such position, and the door must be opened before the latch member can be released.

The arm 38, on the end thereof which is 120 attached to the element 37 is provided with an elongated contact plate 49 that is designed to be engaged by the outer or notched end of the tumbler 15, when the tumblers have been operated by an unauthorized person, thus causing the alarm to be continuously sounded and attract attention to the fact that something is wrong with the machine, so that danger of stealing the machine will be thus reduced to a minimum if 130

not entirely overcome. The lock is of such a construction that a great number of combinations can be obtained, and such combinations readily changed by the owner of

5 the device, and it is thought that the foregoing description, when taken in connection with the drawings will amply set forth the construction, operation and advantages of the improvement.

10 Having thus described the invention, what we claim, is:—

1. In combination with an electric circuit, a normally open switch and a closer therefor; of a casing in which the switch and 15 circuit closer are located, a door for the casing, locking means therefor including a cam which when turned to one position in the operation of the lock will engage the circuit closer to cause the latter to operate 20 the switch to close the circuit, and latching means engaging the circuit closer for holding the same in its last mentioned position.

2. In combination with an electric circuit,

25 a normally open switch and a closer therefor; of a casing in which the switch and circuit closer are located, spring influenced latch means included in the circuit closer, means for holding the latch out of engagement with the circuit closer, a door for the casing, locking means therefor including a cam which when turned to one position in the operation of the lock will engage the circuit closer to cause the latter to actuate 30 the switch and close the circuit, and to also cause the latch to engage with the circuit closer to hold the latter in circuit closing 35 position.

3. In combination with an electric cir-

40 cuit, a normally open switch and a closer therefor; of a casing in which the door and closer are located, spring means for influencing the closer to non-closing position and a pivoted gravity influenced latch sup- 45 ported on the closer, a guide plate having a finger on which the latch normally rests, a door for the casing, locking means therefor including a cam which when turned to one position in the operation of the lock will 50 engage the circuit closer to cause the latter

to influence the switch to close the circuit, and to also permit of the latch gravitating over the closer into engagement with the finger of the guide plate for holding the closer in switch actuating position. 55

4. In combination with an electric circuit and a normally open switch; of a casing in which the switch is located, a spring influenced circuit closer in the casing, guide means therefor including a plate having an upstanding finger against which the closer contacts when the switch is in open position, a latch pivotally secured to the closer having a bifurcated end, one arm of which normally resting on the finger, a door for the casing, locking means therefor including a cam which when turned to one position in the operation of the lock will engage the circuit closer to cause the latter to close the switch and permit of the latch being brought off of the finger of the guide member into contacting engagement with the inner edge of the said finger to hold the closer in position for retaining the switch closed. 70

5. In combination with an electric circuit, 75 a normally open switch and a switch closer; of a casing in which the switch and closer are located, means for latching the closer when in switch operating position, means for normally retaining the closer out of such 80 position, a door for the casing, a tumbler lock thereon, including a cam that is in the path of contact with the closer and designed in the improper operation of the lock to contact therewith to close the circuit and 85 to permit of the latch retaining the circuit so closed, pivoted dogs having operating handles on the outer face of the door normally resting on one of the lock tumblers, and brake means for holding one of said 90 tumblers against free turning, an angle bracket on the door, a latch member in the casing for engaging therewith, and means, operable exteriorly of the casing for moving the latch longitudinally into or out of 95 engagement with the bracket.

In testimony whereof we affix our signatures.

ARTHUR C. SCHLOTH.
HERMAN E. SCHLOTH.
